UNITED STATES PATENT OFFICE.

GEORGE H. GILMAN, OF BELMONT, MASSACHUSETTS.

DRILLING MACHINE.

Application filed June 29, 1921. Serial No. 481,417.

My invention relates to drilling machines and more particularly but not exclusively to a hammer rock drill.

The invention will be best understood from the following description when read in the light of the accompanying drawings of a specific embodiment thereof selected for illustrative purposes, while the scope of the invention will be more particularly pointed out in the appended claims.

Referring to the drawings:—

Fig. 1 shows a longitudinal section through a hammer rock drill;

Figs. 2, 3, 4, 5 and 6 are respectively sections on the lines 2—2, 3—3, 4—4, 5—5 and 6—6 of Fig. 1;

Fig. 7 is a section on the line 7—7 of Fig. 6;

Fig. 8 is a diagram representing the positions of the throttle valve; and

Figs. 9 and 10 are diagrams illustrating the operation of the machine.

Referring to the drawings, I have shown a casing which comprises a cylinder section 1, the chuck casing 3, the ratchet casing 5 and the rear head block 7, these parts or sections being held in assembled relation by means of the three through-bolts 9, extending through suitable perforated lugs 10 formed laterally of the members. For preventing angular movement between the main cylinder section, the chuck casing and the ratchet casing, I provide the dowels 11. These dowels are provided with flanges 13 entering and fitting the recesses 15 in the lugs 10 of the ratchet casing and with sleeve portions 17 which enter the recesses 19 in the adjacent faces of the cylinder section and chuck casing. The bottom of the recesses 19 are flared or are otherwise suitably formed to provide spaces into which the inner ends of the sleeves 17 may be expanded to hold the dowels in position. The dowels thus formed surround the through-bolts 9 or it will be understood may be otherwise suitably formed to permit these bolts to pass by them.

As illustrated the cylinder section is provided with parallel bores 21 and 23, the same opening through the rearward end of the section and being closed by the rear head block 7, while the portion of the cylinder forward of the bores provides the front cylinder head 25.

Herein, in the bore 21 of the cylinder member is reciprocably mounted the head

27 of the hammer piston, and formed integrally with the head is the forwardly projecting shank 29, the exterior cylindrical surface of which fits the bore 31 formed in the front cylinder head 25. This shank serves as a hammer bar and is arranged to strike the rearward end of the shank 33 of the drill steel at the end of the forward movement of the piston.

The shank of the drill steel is shown polygonal in cross-section and is carried in the chuck 35, the latter being provided with tongues 37 fitting the helical grooves 39 extending longitudinally along the hammer bar. Other longitudinally extending grooves 41, which are preferably straight, are formed in the hammer bar and receive tongues 43 formed integrally with the ratchet ring 45, the latter being provided with ratchet teeth 47 engaging the pawls 49. These pawls have perforated bosses 51 through which the through-bolts 9 extend and which bosses fit the bore of the perforations 15 of the lugs 10 on the ratchet casing. The opposed faces of the flanges 13 of the dowels 11 provide bearing surfaces for the pawls. By means of the construction just described, the ratchet ring is prevented from rotating when the piston moves rearwardly, which causes the helical grooves in engagement with the chuck to rotate the drill steel.

Any suitable means for conducting cleansing fluid to the drill hole may be provided and for this purpose I have shown the drill steel provided with a bore 53 which extends from its rearward end face to the cutting point. For injecting water into the bore of the drill steel I provide the usual water tube 55, while air is admitted to the drill steel from a passage 57 in communication with an annular groove 59 formed in the interior surface of the bore 31. From this groove, the motive fluid passes along the grooves 39 and 41 into the chuck chamber 61 at the rear of the drill shank and finds its way into the bore 53 of the drill steel, the flow being more or less restricted by the tongues 37 and 43 of the ratchet ring and chuck fitting these grooves.

For controlling the admission and exhaust of motive fluid to the cylinder chamber at opposite sides of the head 27, I herein provide a distributing valve 65, the latter being tubular or otherwise formed to provide an open ended conduit in communication with

the motive fluid supply inlet 67 for the valve casing. For convenience of manufacture and purposes of renewal, the valve casing is lined with a sleeve 69 having a reduced bore 71 forming an intermediate interior shoulder 73 and in which bore is inserted a second sleeve 75 which fits the bore in a fluid tight manner and abuts the shoulder. For holding these valve casing sections in assembled relation to each other and with the cylinder member I interpose between the end of the sleeve 75 and the rear cylinder head the compression spring 77.

Referring particularly to Fig. 9, the valve 65 is herein provided exteriorly with a central portion 79 of reduced diameter and on each side of this, portions 81 of larger diameter. Between the portions 81 and the ends of the valve the same is formed with an annular groove 83 and a reduced diameter portion 85, the latter adapted to fit the reduced diameter portions 86 of the valve casing. The valve casing is so formed near its opposite ends as to provide annular grooves 87, which by way of the passages 89 communicate with the adjacent end portions of the cylinder. Adjacent each of the grooves 87 are similar annular grooves 91 which are placed in permanent communication with the exhaust passages 93 by means of the slots 95, the exhaust passages leading to the atmosphere in a manner hereinafter described. The valve casing is further provided with a central portion 97 of enlarged diameter, which provides a cylindrical surface fitting the enlarged diameter portions 81 of the valve and from the opposite end portions of the chamber formed by the enlarged diameter portion 97 lead the crossed kicker ports 99 and 100 in communication with the bore 21 of the cylinder. It will be noticed that the valve constructed as described provides at its opposite ends a face or shoulder 101 in constant communication with the intake passage 89 and the face or shoulder 103 which is alternately placed in communication with the passage 89 and the exhaust groove 91.

The operation of the valve is as follows: With the parts in the position illustrated by Fig. 10, motive fluid is admitted from the intake connection 67 into the forward passage 89 by reason of the reduced diameter portion 85 of the valve having moved out of the portion 86 of the valve casing. At the same time, the opposite end of the cylinder is connected to the exhaust groove 91 by reason of the fact that the shoulder portion formed by the reduced diameter portions 83 and 86 has moved out of the partition between the annular grooves 87 and 91. The valve is held in the position illustrated by Fig. 10 by reason of the fact that the forward face 101 is subjected to live air while the rearward face 103 and both the rearward

and forward faces 103 are in communication with the atmosphere. The piston now moves rearwardly until it uncovers the cylinder end of the kicker port 99, which admits live fluid to the rearward end of the chamber 70 formed by the enlarged diameter portion 97 of the valve casing and thereby subjects the rearward face of the rearward enlargement 81 of the valve to live air and, as this face has an area greater than that of the face 75 101, the valve moves forwardly into the position illustrated by Fig. 9. When the valve has moved to this position, the pressure on the surfaces 101 and 103 at the forward end of the valve are balanced by reason of 80 the fact that both are connected to the atmosphere, while the surface 101 at the rearward end of the valve is subjected to live motive fluid and the surface 103 at that end placed in communication with the atmosphere, which locks the valve in position. In this position the motive fluid, which has been admitted to the valve casing through the kicker 99 is then exhausted to the atmosphere by way of the forward end of the cylinder, which is then in communication with the atmosphere.

Admission to the rearward end of the cylinder and exhaust from the forward end now takes place in a manner similar to that described in connection with Fig. 10 and the piston moves forwardly to admit live air to the kicker passage 100, exhaust the kicker passage 99 and repeat the cycle of operations.

For improving the action of the machine, the cylinder is herein provided with the piston controlled exhaust passages 105 in communication with the passages 93. For obviating the effect of leakage from one end to the other of the valve casing chamber receiving the enlarged diameter portions 81 of the valve, the space between said enlarged portions is placed in communication with the exhaust passages 93 by means of passages 107.

When the valve and the piston are in the positions illustrated by Fig. 10, the groove 41 is just about to enter the cylinder, to establish communication between the annular groove 59 and the forward end of the cylinder. When this takes place, the motive fluid flows out of the groove 41 into the front end of the cylinder and acts to keep up the mean effective pressure of the motive fluid therein. Owing to the expansion of the air caused by movement of the piston and wire drawing through the ports, the pressure in the cylinder at the time the groove is in communication therewith is less than the pressure existing in the groove 59. It will be seen that the groove 59 not only acts to supply the bore of the drill steel with fluid but also acts as a seal to prevent escape of motive fluid from the cylinder 130

around the hammer bar or along the grooves formed therein and at the same time provides a convenient means for augmenting the supply to the forward end of the cylinder.

For lubricating the machine the handle 110 which is made integral with the rear cylinder head is shown as provided with a lubricant reservoir 111 and for distributing lubricant from the reservoir for lubricating the moving parts of the machine I provide the plunger 113 having the reduced diameter portions 115 and 117 and mounted to reciprocate in a cylinder provided by the bore 119 formed in the rear cylinder head. This bore is provided with a portion of enlarged diameter 121, which forms a shoulder against which the end of the sleeve 123 inserted into the bore abuts, the sleeve being held in position by a plug 125. The opposite end of the bore 119 is closed by a similar plug 127 having a stop 128 for determining the outward limit of movement of the plunger and between the inner face of the plug and the facing end of the plunger is mounted a compression spring 129 which acts to normally hold the plunger against the end of the sleeve 123. Leading from the reservoir to an intermediate portion of the cylinder for the plunger is a passage 131, while other passages 133 and 135 communicating with the cylinder on opposite sides of the point of communication of the passage 131 respectively place the cylinder in communication with the rear intake and exhaust passage 89 and the interior of the ratchet chamber 5. The sleeve 123 is formed with a lateral port 137 in communication with a passage 139 adapted to be selectively connected by means hereinafter described to either live pressure fluid or to the atmosphere.

Referring to Fig. 9, which shows the position of parts when the passage 139 is connected to live air, the plunger is moved to compress the spring and move against the stop 128 carried by the plug 127. This places the chamber formed by the groove 117 of the plunger in communication with the passage 135 leading to the ratchet casing to supply lubricant to the latter and at the same time the chamber provided by the groove 115 is placed in communication with the lubricant reservoir by way of the passage 131 to fill such chamber. When the passage 139 is connected to exhaust, the motive fluid at the upper end of the plunger as viewed in Fig. 9 escapes and the spring 129 forces the plunger against the end of the sleeve 123. This places the groove 115 in communication with the passage 133, which permits the lubricant to pass through the passage into the passage 89 leading to the cylinder and at the same time the passage 117 is brought in communication with the passage 131 to fill it with lubricant in order

that when the plunger is again moved to the position shown by Fig. 9, lubricant will be supplied the passage 135.

For controlling the machine I show a throttle valve 141 of the turning plug type, the same being provided with a handle 143 for operating it and being seated in a casing connected at the end opposite the handle with the motive fluid supply connection 145. The valve is provided with an internal conduit 147 opening through its end to place it in permanent communication with the supply connection and is provided with exterior slots 149 and 150 for respectively placing the opposite exhaust passages 93 in communication with passages 151 leading to the atmosphere. The construction and operation of the valve is best indicated by Fig. 8, in which the sections correspond to those on the line *a—a, b—b, c—c, d—d* and *e—e* of Fig. 6.

As illustrated by the sections *b—b*, in the plane of the passages 57 and 67 respectively leading to the seal about the hammer bar and to the distributing valve, the internal conduit 147 is placed in communication with the exterior of the valve plug by radial passages 153 and 155, so that when the valve is moved to its first position from the neutral position, in the latter of which neither the passages 57 nor 67 are supplied, the passage 155 will have moved into communication with the passage 57 in order to "blow" the drill-hole. Further movement of the valve moves the passage 153 into communication with the passage 67 leading to the distributing valve but before this takes place interrupts the communication between the passages 155 and 57. For supplying the passage 57 with an amount of air less than that necessary to "blow" the drill hole when the valve is in the full running position, as is illustrated by the third position in Fig. 8, the valve in the plane of the section *c—c* is provided with a radial passage 159 placing the live air conduit 147 in communication with the exterior of the valve and in communication with the passage 159 is the arcual groove 161 formed on the exterior of the valve. The groove 161 is in communication with the passage 57 whenever air is supplied the passage 67 and at all other times it is out of communication with the passage 57.

The exhaust is controlled as heretofore explained by means of the passages 149 and 150 formed in the throttle valve, and as illustrated by the second position of the sections *a—a* and *d—d*, the passages 93 are placed in communication with the exhaust passages 151 just prior to supplying air to the passage 67 leading to the distributing valve and are full open when the valve is in the third or full running position. In the first position when the hole is blown, the exhaust passages are closed to insure that the air supplied will not escape through the

exhaust passages by way of the grooves on the hammer bar and the cylinder.

As illustrated by the sections *e*—*e*, the internal conduit 147 is placed in communication with the exterior of the valve by means of a radial passage 163, while in the same plane as the passage 163 on the exterior surface of the valve is formed an arcual groove 165 and from the valve casing the passage 167 leading to the atmosphere. When the valve is moved to the second position, the arcual groove 165 places the passage 139 leading to the lubricator plunger chamber in communication with the atmosphere by way of the passage 167, which causes the lubricator plunger to move to the end of its stroke opposite that illustrated by Fig. 9. When the valve is moved to the full running position, live air is supplied the passage 139 by way of the passage 163 and communication between the passage 139 and passage 167 is interrupted, which supplies the lubricator plunger chamber with motive fluid to move it to the position illustrated by Fig. 9. It will be noticed that when the throttle valve shuts off the supply of air to operate the hammer, the lubricator chamber is exhausted and the ratchet mechanism is supplied with lubricant, while when the valve is moved to supply air to operate the hammer, the valve is moved to its opposite position to supply the cylinder with lubricant.

This application is an improvement in the rock drills shown in my pending applications Serial No. 421,748, filed November 4, 1920, Serial No. 76,410, filed December 19, 1925, and Serial No. 113,672, filed June 4, 1926, the latter being a division of my application Serial No. 386,868, filed June 5, 1920, which is now Patent No. 1,588,407.

Although I have described one specific embodiment of my invention for illustrative purposes, it is to be understood that extensive deviations from the same may be made without departing from the spirit of my invention.

Claims:

1. In a fluid pressure motor, a cylinder, a piston therein having opposed working surfaces, an imperforate tubular valve having open ends in substantially unobstructed fluid communication with each other, a source of motive fluid supply, conduit means placing said source of supply in constant communication with the interior of said valve, passages controlled by said valve for admitting motive fluid to said cylinder for acting alternately on said opposed working surfaces for actuation of said piston, one of said passages including the interior of said valve, said valve being provided with separate surfaces facing in the same direction, a motive fluid conducting passage for conducting fluid for action on one of said surfaces for creating a pressure condition thereon to move said

valve, a port controlled by said piston for admitting motive fluid to said passage, and means for admitting motive fluid to the other of said surfaces to lock said valve when so moved.

2. In a fluid pressure motor, a cylinder, a piston therein having opposed working surfaces, an imperforate tubular valve having open ends in substantially unobstructed fluid communication with each other, a source of motive fluid supply, passages placing said source of supply in constant communication with the interior of said valve, passages controlled by said valve for admitting motive fluid to said cylinder for acting alternately on said opposed working surfaces for actuation of said piston, one of said passages including the interior of said valve, said valve being provided intermediate its ends with separate surfaces facing in the same direction, a motive fluid conducting passage leading to one of said surfaces for creating a pressure condition thereon to move said valve, a port controlled by said piston for admitting motive fluid to said passage, and means for admitting motive fluid to the other of said surfaces to lock said valve when so moved.

3. In a fluid pressure motor, a cylinder, a piston therein having opposed working surfaces, an imperforate tubular valve having open ends in substantially unobstructed fluid communication, said valve serving to conduct motive fluid for admission to said cylinder for acting on one of said opposed surfaces for actuation of said piston in one direction, means adjacent an end of said valve for controlling admission and exhaust of motive fluid to and from said cylinder for actuation of said piston in one direction, said valve being provided with separate surfaces facing in the same direction, means including a port controlled by said piston for creating a pressure condition on one of said surfaces to cause the valve to move, and means for admitting motive fluid to the other of said surfaces to lock said valve in position when so moved.

4. In a fluid pressure motor, a cylinder, a piston therein having opposed working surfaces, an imperforate tubular valve having open ends in substantially unobstructed fluid communication, said valve serving to conduct motive fluid for admission to said cylinder for acting on one of said opposed surfaces for actuation of said piston in one direction, means adjacent opposite ends of said valve for controlling admission and exhaust of motive fluid to and from said cylinder for acting alternately on said opposed surfaces for actuation of said piston in opposite directions, said valve being provided with separate surfaces facing in the same direction, means including a port controlled by said piston for creating a pressure condition on

one of said surfaces to cause the valve to move, and means for admitting motive fluid to the other of said surfaces to lock said valve in position when so moved.

5. In a fluid pressure motor, a cylinder, a piston therein having opposed working surfaces, an imperforate tubular valve having open ends in substantially unobstructed fluid communication, said valve serving to control motive fluid for admission to said cylinder for acting on one of said opposed surfaces for actuation of said piston in one direction, means adjacent opposite ends of said valve for controlling admission and exhaust of motive fluid to and from said cylinder for acting alternately on said opposed surfaces for actuation of said piston in opposite directions, said valve being provided intermediate its ends with separate surfaces facing in the same direction, means including a port controlled by said piston for creating a pressure condition on one of said surfaces to cause the valve to move, and means for admitting motive fluid to the other of said surfaces to lock said valve in position when so moved.

6. In a fluid pressure motor, a cylinder, a piston therein, an imperforate tubular valve having open ends in substantially unobstructed fluid communication, a passage controlled by said valve for controlling an event of the cycle of said motor, said valve being provided exteriorly thereof with separate surfaces facing in the same direction, a passage controlled by said piston for conducting motive fluid from said cylinder to one of said surfaces to move said valve, and means responsive to the movement of said valve for admitting live actuating fluid to the other of said surfaces to lock said valve when so moved.

7. In a fluid pressure motor, a cylinder, a piston therein, an imperforate cylindrical tubular valve having open ends in substantially unobstructed fluid communication, a passage controlled by said valve for controlling an event of the cycle of said motor, said valve being provided exteriorly thereof with separate surfaces intermediate its ends facing in the same direction, means for conducting motive fluid from said cylinder to one of said surfaces to move said valve, and means responsive to the movement of said valve for admitting fluid to the other of said surfaces to lock said valve when so moved.

8. In a fluid pressure motor, a cylinder, a piston therein having opposed working surfaces, a source of motive fluid, a tubular valve for admitting motive fluid from said source alternately to said cylinder for acting alternately on said opposed surfaces for actuation of said piston, said valve provided with a plurality of surfaces facing in one direction and a plurality of surfaces facing in the opposite direction, means placing the in-

terior of said valve in constant communication with said source, ports and passages controlled by said piston for alternately creating a pressure condition on oppositely facing surfaces to move said valve in opposite directions, and means responsive to motion of said valve for admitting fluid to other of said oppositely facing surfaces to lock said valve when so moved.

9. In a fluid pressure motor, a cylinder, a piston therein, a source of motive fluid supply, an imperforate tubular valve provided with a plurality of surfaces facing in one direction and a plurality of surfaces facing in the opposite direction, means placing the interior of said valve in constant communication with said source, means including ports and passages controlled by said piston for alternately admitting fluid from said cylinder to oppositely facing surfaces to move said valve in opposite directions, and means responsive to motion of said valve for admitting fluid to other of said oppositely facing surfaces to lock said valve when so moved.

10. In a fluid pressure motor, a cylinder, a piston therein, a source of motive fluid supply, having opposed surfaces, an imperforate tubular valve, means placing the interior of said valve through one end thereof in constant communication with said source, means adjacent the ends of said valve for controlling the admission of motive fluid to said cylinder for acting alternately on said opposed surfaces, a plurality of surfaces on said valve facing in one direction, a plurality of other surfaces facing in the opposite direction, all of said surfaces being intermediate the ends of said valve, means responsive to motion of said piston for alternately creating a pressure condition on oppositely facing surfaces to move said valve in opposite directions, and means responsive to motion of said valve for admitting fluid to other of said oppositely facing surfaces to lock said valve when so moved.

11. In a fluid pressure motor, a cylinder, a piston therein, having opposed surfaces, a source of motive fluid supply, an imperforate tubular valve, means placing the interior of said valve through one end thereof in constant communication with said source, means adjacent the ends of said valve for controlling the admission and exhaust of motive fluid to and from said cylinder for acting alternately on said opposed surfaces, a plurality of surfaces on said valve facing in one direction, a plurality of other surfaces facing in the opposite direction, all of said surfaces being intermediate the ends of said valve, means including ports and passages controlled by said piston for alternately creating a pressure condition on oppositely facing surfaces to move said valve in opposite directions, and means responsive to motion of said valve for admitting fluid to other of

said oppositely facing surfaces to lock said valve when so moved.

12. In a fluid pressure motor, a cylinder, a piston therein having opposed surfaces, a source of motive fluid supply, an imperforate tubular valve, means placing the interior of said valve through one end thereof in constant communication with said source, means adjacent the ends of said valve for controlling the admission of motive fluid to said cylinder for acting alternately on said opposed surfaces, a plurality of surfaces on said valve facing in one direction, a plurality of other surfaces facing in the opposite direction, all of said surfaces being intermediate the ends of said valve, means responsive to motion of said piston for alternately admitting fluid from said cylinder on oppositely facing surfaces to move said valve in opposite directions, and means responsive to motion of said valve for admitting fluid to other of said oppositely facing surfaces to lock said valve when so moved.

13. In a fluid operated motor, a cylinder, a piston therein, a cylindrical valve, means connecting a source of motive fluid to opposite ends of said valve, exhaust ports adjacent said ends, cylinder supply and exhaust ports intermediate said ends and said exhaust ports, oppositely facing shoulders on said valve adjacent each end, one of said shoulders being in constant communication with the adjacent exhaust passage and the other alternately in communication with said exhaust passage and said source, and means responsive to the motion of said piston for moving said valve.

14. In a fluid operated motor, a valve casting, a valve having an internal conduit, means permanently connecting said conduit to a source of motive fluid supply, an exhaust port communicating with said casting, a cylinder supply and exhaust port communicating with said casting, means providing oppositely facing shoulders on said valve adjacent said ports, one of said shoulders being in constant communication with said exhaust port, means for moving said valve, and means responsive to such movement for placing the other of said shoulders in communication with said source and the interior of said valve in communication with said cylinder supply and exhaust port.

15. In a fluid operated motor, a cylinder, a valve and its casing, a passage connecting said casing with an end of said cylinder, an adjacent passage connecting said casing with the atmosphere, a third passage connecting said casing to a source of motive fluid supply, means for moving said valve alternately into two positions, said valve and its casing formed to provide means for connecting said first mentioned passage to said third passage when said valve is in one of said positions and to said adjacent passage when in the

other of said positions, said means providing a pair of oppositely facing surfaces on said valve, one of said surfaces being in constant communication with said first mentioned passage and the other in constant communication with said adjacent passage.

16. A fluid pressure motor having, in combination, a cylinder having parallel bores and a piston having opposed working surfaces in one of said bores, a tubular valve in the other of said bores, said valve having open ends in fluid communication with each other by way of the interior of said valve, passages connecting the bore containing said valve at opposite end portions thereof with said cylinder for conducting motive fluid to said bore for said piston for acting alternately on said opposed working surfaces, conduit means placing the interior of said valve in fluid communication with a source of motive fluid supply through one of the open ends of said valve, said valve having opposed working surfaces intermediate its ends, conduit means including ports controlled by said piston for admitting motive fluid to the bore for said valve for acting alternately on said opposed working surfaces of said valve for actuating said valve in opposite directions, said valve and the bore for said valve at opposite ends thereof having cooperating portions controlling admission of motive fluid alternately to said passages around the ends of the valve including a part upon said valve exposed to the motive fluid only when said motive fluid is flowing into the associated passages.

17. In a fluid pressure motor, a cylinder, a piston therein, an open ended reciprocatory tubular valve, a source of motive fluid connected to an end of said valve, a valve casing, passages leading from said casing to opposite ends of said cylinder, means for reciprocating said valve in synchronism with said piston, said valve and its casing being constructed with cooperating valve faces and valve seats to cause said valve to connect said passages alternately to said source, a passage adjacent each of said first named passages placing said valve casing in communication with the atmosphere, and an annular projection carried by said valve adjacent each of the pairs of passages so formed, means for moving said valve to cause said projections alternately to establish and interrupt communication between the passages of each pair, and said projections being so formed and disposed as to move into the passage leading to the cylinder of each pair when such communication is established.

18. In a fluid pressure motor, a cylinder, a cylindrical valve, a casing for said valve, conduit means connecting said casing to an end portion of said cylinder, said valve and casing affording means for alternately connecting those ends of said conduit means in

- communication with said casing to a source of live motive fluid and to the atmosphere, a locking surface for said valve in constant communication with said conduit means, 5 pressure surfaces on said valve other than said locking surface, and means for creating pressure conditions on the last named surfaces to cause said valve to move.
19. A percussive tool having, in combination, a cylinder, a piston having a head and a shank, a cylinder having large and small diameter portions fitting said head and shank, means controlled by said head for admitting motive fluid directly to said large 10 diameter portion of said cylinder for acting upon said head for moving the piston in one direction, and means controlled by said shank for admitting motive fluid to said large diameter portion of said cylinder by 15 way of said small diameter portion of said cylinder for acting upon said head for moving said piston in the same direction.
20. A percussive tool having, in combination, a cylinder, a piston having a head and a shank, a cylinder having large and small diameter portions fitting said head and shank, a fluid actuated valve controlled by 25 said piston for admitting motive fluid directly to said large diameter portion of said cylinder for acting upon said head for moving the piston in one direction, and means controlled by said shank for admitting motive fluid to said large diameter portion of said cylinder by 30 way of said small diameter portion of said cylinder for acting upon said head for moving said piston in the same direction.
21. In a rock drill, a cylinder, a hammer reciprocably mounted in said cylinder, a 35 valve for admitting motive fluid to an end of said cylinder for initiating motion of said piston, and means controlled in response to motion of said piston so initiated for admitting additional motive fluid to the same end 40 of said cylinder.
22. In a rock drill, a cylinder, a piston having a head portion and a shank portion, a valve for admitting motive fluid to act on one of said portions for initiating movement 45 of said piston, and means directly controlled by the other of said portions for admitting motive fluid to act on the said one portion after such initiation of movement.
23. In a rock drill, a cylinder having 50 communicating larger and smaller diameter portions, a piston in said cylinder and having a head and a shank respectively fitting said larger and smaller diameter portions, a source of gaseous motive fluid supply, means for 55 admitting motive fluid from said source to the large diameter portion of said cylinder for reciprocating said piston, and a gaseous seal about said shank for preventing escape of motive fluid from said larger diameter portion past said shank.
24. In a rock drill, a cylinder having communicating larger and smaller diameter portions, a piston in said cylinder and having a head and a shank respectively fitting said larger and smaller diameter portions, a source of gaseous motive fluid supply, means for admitting motive fluid from said source to the large diameter portion of said cylinder for reciprocating said piston, a gaseous seal about said shank for preventing escape of motive fluid from said larger diameter portion past said shank, and means controlled by said shank for at times placing said seal in communication with said larger diameter cylinder portion.
25. In a rock drill, a cylinder having communicating larger and smaller diameter portions, a piston in said cylinder and having a head and a shank respectively fitting said larger and smaller diameter portions, a source of gaseous motive fluid supply, means for admitting motive fluid from said source to the large diameter portion of said cylinder for reciprocating said piston, a gaseous seal about said shank for preventing escape of motive fluid from said larger diameter portion past said shank, conduit means for conducting fluid to the drill hole, and means for establishing communication between said seal and said conduit means.
26. In a rock drill, a cylinder having larger and smaller diameter portions, a piston having a head fitting said larger diameter portion and a shank provided with a longitudinally extending groove and fitting said smaller diameter portion, means placing said groove in continuous communication with a source of live motive fluid supply, and means for moving said groove into and out of communication with said larger diameter cylinder portion.
27. In a rock drill, a cylinder having larger and smaller diameter portions, a piston having a head fitting said larger diameter portion and a shank provided with a longitudinally extending groove and fitting said smaller diameter portion, means placing said groove in communication with a source of live motive fluid supply, means for moving said groove into and out of communication with said larger diameter cylinder portion, a drill steel having a bore and operated by said piston, and means for establishing communication between said groove and the bore of said steel.
28. In a rock drill, a cylinder having larger and smaller diameter portions, a piston having a head fitting said larger diameter portion and a shank provided with a longitudinally extending groove and fitting said smaller diameter portion, conduit means placing said groove in continuous communication with a source of motive fluid supply, means for moving said groove into and out of communication with said larger diameter cylinder portion.

- diameter cylinder portion, a chuck, a ratchet for rotating said chuck, and one or the other of said chuck and ratchet having a tongue co-operating with said groove.
29. In a rock drill, a cylinder having larger and smaller diameter portions, a piston having a head fitting said larger diameter portion and a shank provided with a longitudinally extending groove and fitting said smaller diameter portion, conduit means placing said groove in continuous communication with a source of motive fluid supply, means for moving said groove into and out of communication with said larger diameter cylinder portion, a chuck, a ratchet for rotating said chuck, one or the other of said chuck and ratchet having a tongue cooperating with said groove, a drill steel having a bore and operated by said piston, and means for establishing communication between said groove and the bore of said steel.
30. In a rock drill, a casing, a piston in said casing having a hammer bar, said casing having provision for carrying a hollow drill steel, a passage formed in said hammer bar for conducting motive fluid to the bore of said steel, motive fluid distributing means for actuating said piston, valvular mechanism for controlling the motive fluid supply to said means, valvular mechanism for controlling a supply to said passage, and means coordinating said valvular mechanisms whereby said passage and distributing means may be simultaneously supplied or the former supplied to the exclusion of the latter.
31. In a rock drill, a casing, a piston in said casing having a hammer bar, said casing having provision for carrying a drill steel having a bore, a passage formed by said hammer bar for conducting motive fluid to the bore of said steel, motive fluid distributing means for actuating said piston, valvular mechanism for controlling the motive fluid supply to said means, valvular mechanism for controlling a supply to said passage, and means coordinating said valvular mechanisms and so constructed and arranged to supply both said passage and distributing means simultaneously or to increase the supply to said passage and to interrupt the supply to said distributing means.
32. In a drilling machine, a cylinder member having integral portions providing parallel bores, a handle member for said cylinder member and located rearwardly of the same, a piston in one of said bores, an open ended tubular valve in the other of said bores and for controlling the admission to opposite ends of said cylinder, said valve having its ends in fluid communication by way of the interior of said valve, a motive fluid supply connection at the end of said valve remote from said handle, and a throttle valve for said supply connection and located forwardly of said valve.
33. In a drilling machine, a cylinder member having a front cylinder head carrying a throttle valve, parallel bores in said member each opening through the rearward end thereof, a member extending over the open ends of both bores, a tubular valve in one of said bores, a piston in the other of said bores, and a motive fluid connection between said throttle valve and tubular valve.
34. In a rock drill, a casing having provision for carrying a drill steel, a hammer piston in said casing, a rotary chuck carried by said casing, means for rotating said chuck comprising a ratchet ring surrounding said hammer piston, a pawl cooperating with said ratchet ring, said casing being sectional and comprising a section surrounding said ratchet ring, a bore in said section containing said pawl, an aligned bore in the adjacent section, a sleeve fitting both bores and providing an end bearing for said pawl, a side bolt for holding said sections together, said side bolt passing through said sleeve and pawl.
35. In a rock drill, a cylinder, a piston in said cylinder, conduit means for establishing communication between the interior of said cylinder and the atmosphere, a chuck formed for carrying a hollow drill steel, a hammer bar carried by said piston and extending into said chuck, a conduit means formed in said hammer bar and leading to the interior of said chuck, conduit means leading to the interior of said cylinder for conducting fluid thereto from a source of motive fluid supply, and means for preventing flow through said first and last named conduit means and connecting said source to said second named conduit means.
36. A hammer rock drill having in combination, a cylinder, a hammer piston in said cylinder, a valve casing, a reciprocatory tubular valve in said casing, said valve having open ends in fluid communication with each other, a motive fluid supply connection for constantly supplying the interior of said valve with motive fluid through one end thereof, said valve being arranged with its axis substantially parallel to the axis of said piston, passages connecting said casing at the end portions of said valve with the adjacent end portions of said cylinder, passages connecting said casing with the atmosphere and communicating with said casing at points adjacent the points of communication of said first named passages with said casing and between said last named points and the longitudinal center of said valve, valve seats on said casing at the ends of said valve, the end portions of said valve cooperating with said seats for alternately establishing and interrupting communication between said passages connecting said casing with the end portions of the cylinder and the motive fluid supply,

- valve seats on said casing between the last named passages and said passages connecting said casing with the atmosphere, annular enlargements at the end portions of 20
6 said valve cooperating with said last named valve seats for alternately establishing and interrupting communication between said passages and oppositely facing pressure surfaces on said valve and cooperating 25
10 conduit means directly controlled by said piston for reciprocating said valve.
37. A rock drilling machine having in combination, a cylinder having a large diameter bore and a small diameter bore, a 30
15 hammer piston having a head fitting said large diameter bore and a hammer bar fitting said small diameter bore, a chuck, mechanism for causing said hammer piston by
- its movement to rotate said chuck, said mechanism including grooves on said hammer bar which establish communication between the forward end of said cylinder and said chuck, an annular groove in the surface of said smaller diameter bore, a motive fluid supply connection for said machine, means for alternately admitting and exhausting motive fluid from said supply connection to and from opposite ends of said large diameter bore, and conduit means in communication with said motive fluid supply connection for supplying live motive fluid to said annular groove.
- In testimony whereof, I have signed my name to this specification.

GEORGE H. GILMAN.
